FEED ROLL DRIVE AND BRAKE MECHANISM THEREFOR FOR PRESSES OF THE PUNCH AND BLANKING TYPE

Ewell W. Forkner, Cincinnati, Ohio, assignor to Precision Flexopress Corporation, Cincinnati, Ohio, a corporation of Ohio

Application July 27, 1953, Serial No. 370,566

2 Claims. (Cl. 271—2.4)

This invention relates to presses of the punch and blanking type, and more particularly to feed roll drives and brake mechanisms therefor.

An object of this invention is to provide a feed roll drive and brake mechanism therefor for intermittently feeding sheet metal stock to punch and blanking presses.

Another object of this invention is to provide a feed roll mechanism of the type set forth in the preceding object, that is provided with an intermittent drive and a brake for the feed rolls, the brake and drive being so arranged that the brake is released slightly in advance of the beginning of the feed stroke of the drive for the rolls, and is applied slightly after the feed stroke of said drive has been completed, to thereby positively prevent over-running of the feed rolls but, at the same time, allowing a slight amount of creep of the stock while the die pilots are centering the stock in preparation for the press or punch elements of the die to strike the stock.

Another object of the invention is to provide a feed roll drive, as set forth in the preceding object, in which the brake is applied slightly in advance of the separation of the feed rolls.

A still further object of the invention is to provide a novel arrangement for adjusting the minimum clearance of the feed rolls to accommodate stock of various gauges, without changing the lift of one of the feed rolls when moved to a position where it is disengaged from the stock.

Other objects of the invention will be apparent to those of ordinary skill in the art to which the invention pertains, from the following description and drawings.

In the drawings:

Figure 1 is a view in side elevation of a press of the punch and blanking type, showing the feed roll drive mechanism, the brake mechanism and the mechanism for separating one feed roll from the other to effect intermittent feeding of stock in timed relation to the crank shaft of the press, as arranged in accordance with an embodiment of the invention;

Fig. 2 is a partial view in section, taken on line II—II of Fig. 1, illustrating in top plan view the lever which controls the brake, and the lever which separates one feed roll from the other, and the mechanism whereby the minimum gap between the feed rolls may be adjusted;

Fig. 3 is a view in section, taken on line III—III of Fig. 1, showing the feed rolls and the mechanism whereby the minimum separation thereof may be adjusted, and the drive therefor;

Figs. 4 and 5 are views in section, taken on lines IV—IV and V—V of Figs. 2 and 1, respectively; and

Fig. 6 is a side view of the feed roll gear drive as seen looking in the direction of arrows VI—VI of Fig. 3.

In Fig. 1 of the drawings is illustrated a press 1 of the punch and blanking type, having a frame 2 at the front of which is mounted a punch press ram 3 for vertical reciprocating motion in guideways 4, only one

2

of which is shown. The ram 3 is connected by a connecting rod 5 to a crank shaft, the center of which is at 6. Outside the frame 2, the crank shaft has mounted thereon cams 7 and 7', and a drive disk or block 8, having an adjustable-length crank 9 and crank pin 10, to which a rack bar 11 is attached. Cams 7 and 7' control stock feed rolls and a brake therefor, as will appear infra. The rack bar 11 is provided at its lower end with rack teeth 12, that mesh with the teeth of a pinion 13, forming part of a one-way clutch 14. The pinion 13 is rotatably mounted on a stub shaft 15, which is a part of a driving element 15' of the one-way clutch 14. On the feed stroke, the driving element 15' is coupled to the driven element 15a of the clutch by clutch rollers 15b. The driven element 15a is secured to stub shaft 15 of the feed roll 16.

As the crank shaft rotates in the direction of arrow 17, the rack bar 11 is reciprocated. On the up or feed stroke of the rack 11, pinion 13 turns in the direction of arrow 18, whereby the driven element 15a is turned in the direction of that arrow. On the return stroke of the rack bar 11, pinion 13 turns in the direction opposite to that of arrow 18. Since the pinion is coupled by means of the one-way clutch to feed roll 16, the driving connection between the pinion and the feed roll is disengaged on the return stroke of the rack bar 11.

Cooperating with the feed roll 16 is another feed roll 20. Feed roll 20 is driven by feed roll 16 through a drive including gears 21 and 22, which are secured to the stub shafts 23 and 24, respectively, of rolls 16 and 20. Roll 20 is supported by rods 25 and 26 from levers 27 and 28. The stub shafts 24 and 24' of roll 20 operate in windows 0 in the side frame members 2. Levers 27 and 28 are secured to an eccentric, comprising a cylinder 29 that is disposed about a shaft 30. On shaft 30, and within cylinder 29, eccentrics 31 and 32 are keyed to shaft 30. By turning shaft 30, eccentrics 31 and 32 are turned, thereby raising or lowering the cylinder 29. As cylinder 29 is raised or lowered, the levers 27 and 28 and feed roll 20 are likewise raised or lowered. By adjusting cylinder 29 and the eccentrics 31 and 32, the minimum gap 33, between the feed rolls 16 and 20, may be adjusted to accommodate the particular thickness of sheet stock being fed to the press. The sheet stock delivered to the rolls 16 and 20 may be guided by means of guides, not shown, at the rear of the press, to keep the same centered on the feed rolls 16 and 20.

When sheet stock has been fed in the required amount to the press, feed by the rolls must be arrested. Also, the pressure of the rolls 16 and 20 should be relieved in order to allow the stock to feed by creeping slightly, as the punch or pressing operation is being performed on that stock.

To effect the release of pressure on the stock, mechanism is provided for raising roll 20 off the stock when the feed is to be arrested. As shown in Fig. 1, that mechanism comprises a lever 34 that is keyed to cylinder 29. The free end of lever 34 is provided with a cam follower roller 35, that rides on the surface of cam 7, including the cam lobe 36 thereof. As the crank shaft rotates in the direction of arrow 17, the lever 34 is depressed when point A of the cam lobe 36 passes over cam follower roller 35. The lever 34 and cylinder 29 are thereby turned counterclockwise, as seen in Fig. 1, whereby the levers 27 and 28 and the lift rods 25 and 26 raise feed roll 20 out of engagement with the stock. The feed roll 20 will remain in that elevated position until point B of the cam lobe 36 passes out of contact with the cam follower roller 35.

The gears 21 and 22 are maintained in driving relation by the gear drive and radius arm arrangement shown in

Fig. 6. Gear 21, as stated, is the driven gear, and it drives a gear 21a mounted on a fixed shaft 21e secured to a side frame member 2. Gear 21a drives a gear 21b mounted on a fixed shaft 21d secured to the side frame member 2. Gear 21b drives gear 22 of roll 20. The shaft center of gear 22 and of roll 20 is fixed with relation to the center of shaft 21d by a radius arm 21c coupled to lift rod 26. Thus as the roll 20 and gear 22 are raised and lowered by lift rods 25 and 26, the center for roll 20 and gear 22 rotates about the center of shaft 21d thereby 10 maintaining a positive drive for roll 16 and roll 20 at all times.

In order to prevent over-travel of the feed rolls 16 and 20 while the feed roll 20 is out of engagement with roll 16, a brake mechanism, controlled by cam 7', is provided that includes a band brake 38, one end of which is anchored to a bolt 39, secured to a bracket 40 attached to the frame of the press, and the other end of which is connected by a pin 41 to a brake rod 42. Band brake 38 works on the driven element 15a of clutch 14. The upper end of the brake rod 42 is connected by a pin 43 to a lever 44 that is secured to the frame of the machine on a stub shaft 45. Lever 44 has at its free end a cam follower roller 46 that rides on the surface of cam 7', including its lobe 36b.

Cam lobe 36 is active between points A and B, and is so located in relation to the downstroke of the punch press ram 3 that, when point A has traveled to the position where it engages cam follower roller 35, the feed roll 20 will be lifted from the stock just before the punch press ram reaches the bottom of its stroke, or just before the die pilots engage and center the stock. Cam lobe 36 remains in engagement with cam follower roller 35 until point B of the lobe passes off the roller. When point B has passed off roller 35, the upper feed roll 20 is lowered into engagement with the sheet stock being fed to the press. At this point, the upstroke of the rack bar 11 and the feed of stock by rolls 16 and 20, are about to commence.

Cam lobe 36b extends from points A' to B', substantially 180°. Point A' reaches cam follower roller 46 slightly in advance of the time that point A of cam lobe 36 reaches cam follower roller 35. Therefore, the brake band 38 will be applied to stop the feed rolls the moment cam lobe 36 engages cam follower roller 35 to lift roll 20 off the sheet being fed to the press. Therefore, by applying the brake in this manner, there is no possibility of over-feeding of the stock to the press. The brake band 38 is applied all the time that cam lobe 36b is in engagement with cam follower roller 46. Therefore, the brake will be applied during the entire return stroke of the rack bar 11, and for a short while after the rack bar 11 has commenced its up or feed stroke.

In order to assure positive release of the brake when the cam lobe 36b has passed over follower roller 46, a tension spring 47 is provided. One end of that spring is secured to a pin 48, attached to the side frame of the machine, and the other is attached to the brake rod 42. The length of the brake rod 42 may be adjusted by means of a threaded connection 49 and a lock nut 50, to thereby adjust the brake band for clearance and working pressure.

As stated supra, the eccentrics 31 and 32, and the cylinder 29, provide the adjustment of minimum gap of feed rolls 16 and 20. The adjustment may be pre-set, as shown in Fig. 1, by means of a handle 51 secured to the outer end of shaft 30, and an index ring 52 provided with spaced notches 53 for receiving a spring-pressed pin 54 at the outer end of handle 51. When handle 51 is in the position shown in Fig. 1, the minimum space or gap between rolls 20 and 16 is at the minimum value. By turning the handle in the direction of arrow 55, the minimum gap may be increased to suit the thickness of stock to be fed. Adjusting the eccentric does not, however, change the clearance between cam lobe 36 and cam follower 35; therefore, the lift of feed roll 20 remains con-

stant, regardless of what the minimum gap adjustment between rolls 16 and 20 is.

Having thus described the invention, it will be apparent to those of ordinary skill in this art to which it pertains, that various changes and modifications may be made in the illustrated embodiment thereof without departing from either the spirit or the scope of the invention.

Therefore, what is claimed as new and desired to be secured by Letters Patent is:

1. A feed roll drive for intermittently feeding sheet stock to punch and blanking presses and the like, said presses having a frame and a crank shaft rotatably supported thereby, for actuating the ram of the press, said feed roll drive comprising a pair of rolls rotatably supported, one above the other, in the path of travel of the stock to be fed to the press, one of said rolls being rotatable but fixed in a vertical plane with respect to the other roll, and the other of said rolls being movable in said vertical plane above the first-mentioned roll, said rolls being gear-connected so as to be positively driven together, a one-way clutch on the shaft of the fixed roll, a pinion on said clutch, a rack bar meshing with said pinion, the rack bar being adapted to be driven in timed relation of the crank shaft, to drive said roll through said one-way clutch during the up-stroke of the rack bar means for adjusting said rolls to provide a predetermined minimum spacing between them, means operating in timed relation with the down stroke of the rack bar for lifting said movable roll vertically while maintaining said rolls in driving relationship, a brake on said fixed roll shaft, and means timed with the upstroke of said rack bar, to apply said brake and stop the roll at the beginning of, and during, the downstroke of said rack, and to release said brake at approximately the commencement of the upstroke thereof.

2. A feed roll mechanism for presses of the punch and blanking type, provided with crank shafts, comprising a pair of gear-connected rolls mounted one above the other, and adapted to feed stock to the press, means for intermittently driving said rolls, a lift rod at each end of the upper roll for raising and lowering the same, a shaft, an eccentric on the shaft and secured thereto, and a cylinder on the eccentric, lever arms fast on the cylinder and connected to said lift rods, means for turning said shaft to raise or lower said cylinder and said upper feed roll, means connected to the cylinder on said eccentric shaft for turning the cylinder and thereby raising and lowering the same while maintaining the rolls in driving relation, said means being adapted to operate in timed relation with the down and upstrokes, respectively, of the press crank shaft to disengage and engage the stock to be fed, said raising and lowering means comprising a first cam adapted to be driven by the crank shaft and a lever connected to the cylinder on said eccentric shaft and having a cam follower operated by said cam, and means for applying a braking force to one of the rolls to stop the same when the upper roll is raised out of feeding engagement with said stock, said brake applying means comprising a second cam adapted to be driven in timed relation to the crank shaft, a pivotally mounted brake-actuating lever having a cam follower adapted to engage said second cam, and a rod connecting the brake-actuating lever and adapted to apply the braking force, said cam followers being so positioned that the cylinder on the eccentric shaft is turned slightly in advance of the brake rod-actuating lever, and the brake-actuating lever is held in braking position for an interval after the eccentric lever is off the first cam, the brake-actuating means being operative to release the brake when the eccentric shaft is turning in a direction to lower the upper roll into engagement with the stock on the fixed roll.
